UNITED STATES PATENT OFFICE.

ELI H. LEE, OF MONROVIA, CALIFORNIA.

GAME.

Application filed March 23, 1927. Serial No. 177,532.

This invention relates to amusement devices, and more particularly to an indoor game. It is an object of this invention to provide a game that is played upon a specially constructed table having marginal, resilient cushions, a plurality of pockets at one end thereof, the players playing the game with the conventional type of ivory billiard ball and cue.

10 A still further object of this invention is to provide a game of skill that will prove to be extremely interesting and recreational to the players thereof, and which may be played solely from one end of the table so that the 15 same may be installed either in a room having small dimensions, since the players are not obliged to walk around the table in playing the game; or, it may be installed in a narrow gallery similar to a shooting gallery—the 20 walls of the gallery being adjacent the longitudinal edges of the table. To this end the invention contemplates a simple, practical and durable billiard table which is designed with certain features that lend interest and 25 enchantment to the game.

With these and many other objects in view, which will more readily appear as the nature of this invention is better understood, the same consists in the novel construction, combination, and arrangement of parts which will hereinafter be more fully described, illustrated and claimed.

The essential features of the invention involved in the carrying out of the objects indicated are susceptible to modification; but a preferred embodiment of the invention is shown in the accompanying drawings, in which:—

40 Figure 1 is a perspective view of the apparatus for playing my improved game, and Fig. 2 is a sectional view taken along the lines 2—2 of Figure 1.

These two figures in the drawings are deemed sufficient to clearly illustrate the nature of my invention, and the reference numeral 1 designates the body portion or top of the table, and this table has supporting legs 2, 3, 4 and 5, which legs are carefully constructed and are of heavy material, so that 45 the surface of the table 1, may lie in an accurate, horizontal plane. The surface of the table may be of any desirable material. However, I prefer to cover or veneer this surface with a sheet of heavy iron, and cover this 50 iron with a sheet of felt 6. This felt may be of any color, but I prefer to employ a

soft and durable felt of green color, as this color is restful to the eye and is the conventional type of felt used in all manner of games of this nature. One end of the table has a 60 pair of converging sides 7 and 8, which sides terminate at 9. The sides 7 and 8 are formed preferably of a symmetrical design. A marginal, upstanding flange 10 extends around the periphery of the table and on the inner 65 surface of this flange there is fastened if desired, a suitable, resilient strip of material. The continuity of this resilient strip is interrupted at points along the sides 7 and 8, where there are formed a plurality of 70 pockets 11, 12, 13, 14 and 15 respectively, and at a point diametrically opposed from the pocket 13, there is formed a pocket 17. Beneath the surface of the table there is an inclined tray or chute 22 communicating each 75 of the pockets 11, 12, 13, 14 and 15 with a dispensing pocket 20 located on the side of the table beneath the pocket 17 or thereabouts. The pocket 17 communicates with this inclined chute by means of a chute 21, so clearly indicated in Figure 2. The dispensing pocket is so constructed that only one ball within the chute 22 is visible, and when that ball has been removed from the pocket 20, the ball next to it becomes visible, but no 80 others, and this feature constitutes an important part in the playing of the game. A suitable board 23 extends across the table 85 beneath the same, between the supports 2 and 3 to support the end of the chute 22, and aids in concealing the balls within the chute. The side wall of the pocket 13 is U-shaped and the 90 surface of the table extends inwardly between the side walls of this pocket a considerable distance, and the pocket is formed rearwardly between the U-shaped sides. A pair 95 of marks are formed upon the table surface as at 25 and 26. These marks correspond to 100 the set-up points whereby my improved game may be commenced.

Various games may be played upon my improved billiard table, and anyone possessing such a table is at liberty to invent various games that he may play to amuse himself. I prefer however, to play the game which will be described in this specification. I prefer to call my improved game, "the game of Taft." In connection with this game I employ suitable balls of different colors, and the players make their strokes upon this ball with the conventional type of cue. The players indulging in this game may use any suit-

able means for determining the order of their rotation such as flipping a coin or performing certain competitive feats upon the table with the balls. However, the method employed is not contemplated in this invention, and any suitable optional method may be agreed upon. The player who commences the game, places a ball upon each of the points 25 and 26, which points are marked upon the 10 table; and using the ball upon the spot 25 for a cue-ball, the player plays upon the ball resting upon the point 26. The ball upon the point 26 is referred to as a "table ball" while the other is referred to as a "cue ball." 15 Each of the pockets 11, 12, 14 and 15 have relative values in counting the scores of the players, and the pocket 13 may be called the "Taft" pocket.

The object of the game is, 1st, to knock 20 the table-ball into one of the pockets 11, 12, 14 or 15, and the score is given the player for doing this according to the pocket made. In order to score upon the pocket 17, the player must make a "double cushion bank" and a 25 relatively high tally is given him for making this shot. The "Taft" pocket may be the prize pocket, and when a prize is played for, a tally is recorded upon this pocket by hitting the table-ball and putting the cue-ball 30 in the "Taft" pocket. This similarly may give the player a relatively high tally for the shot. Should the player at any time knock the table-ball into the "Taft" pocket, he is assumed to have made what is called a "scratch" 35 and a penalty is provided for committing this offense, and the player may lose this shot or any "Taft" which he may have executed before. Similarly, the cue-ball in the pockets 11, 12, 14 and 15 may be termed a "scratch." 40 The game may be continued indefinitely to any number of points such as fifty or a hundred or more, and the number of points played for is optional. A plurality of spaces may be provided at one end of the table. These 45 spaces are designated by the reference numeral 30, and as each player begins his shot, he

may remove a ball from the dispensing pocket, place the same in one of the squares to which his ball corresponds, and commence his shot from that point. As stated before, the dispensing pocket does not permit the player to see for which space he must make his next shot, as only one ball is visible within the pocket at a time.

My invention is susceptible to a great number of modifications, and I contemplate various changes in the size, workmanship, construction and other various features of the game. Only in so far as I have particularly pointed out my invention and limited myself in the appended claims, do I desire to limit myself.

Having thus described the invention, what is claimed and desired to be secured by Letters Patent, is:

1. A game table comprising an elongated, horizontal top having one end V-shaped and the other end rectangular, a marginal upstanding flange surrounding said table top, a pocket in said rectangular end, a pocket in the apex of said V-shaped end, said pocket being relatively narrow, a pocket located centrally of each side of said V-shaped end, and a pocket located in the outer end of said V, and a plurality of squares indicated on said table 70 adjacent said rectangular end as and for the purpose specified.

2. A game table comprising an elongated horizontal top having one end V shaped and the other end rectangular, a marginal upstanding flange surrounding said table top, a pocket in said rectangular end, a pocket in the apex of said V shaped end, and a pocket located in each side of said V shaped end and a pocket located in the outer ends of said V 80 and a plurality of squares indicated on said table adjacent said rectangular end as and for the purpose specified.

In testimony whereof I have signed my name to this specification.

ELI H. LEE.
